UNITED STATES PATENT OFFICE.

SIEBOLD R. MENSSEN, OF DAVID CITY, NEBRASKA.

HANDY MEASURE.

1,317,030.

Specification of Letters Patent. Patented Sept. 23, 1919.

Application filed July 25, 1918. Serial No. 246,748.

To all whom it may concern:

Be it known that I, SIEBOLD R. MENSSEN, a citizen of the United States, residing at David City, in the county of Butler and 5 State of Nebraska, have invented certain new and useful Improvements in Handy Measures, of which the following is a specification, reference being had therein to the accompanying drawing.

10 This invention relates to a measuring device which is especially adapted for use in connection for measuring ribbons, tapes and any other material which is wound upon wheels or the like.

15 Another object of this invention is the production of a simple and efficient bracket for supporting the measuring tape upon the ribbon carrying case.

In the drawings:—

20 Figure 1 is a front elevation of the case, the measuring device being supported thereon.

Fig. 2 is a section taken on line 2—2 of Fig. 1.

25 Fig. 3 is a detail perspective of one end of the measuring tape supporting bar.

Fig. 4 is a detail perspective of the sliding shoe which carries the measuring tape reels.

30 Fig. 5 is a top plan view of the measuring tape reels mounted upon the supporting track.

Fig. 6 is a plan view of the blank from which the reel supporting clip is formed.

35 By referring to the drawings it will be seen that 1 designates the case which supports a plurality of tape supporting reels 2. A cover 4 is hingedly secured to the casing 1 and carries a lid 3 having a glass panel 5 mounted thereon. The casing 1 is provided

40 with a longitudinally extending slot 6 along the front edge thereof and the ribbons extend through this slot 6 for the purpose of permitting the ribbons or tapes 7 to be 45 unwound from the reels 2.

A bracket 8 is secured near each end of the casing and each bracket 8 is provided with an off-set outwardly extending end 9. A track plate 10 preferably formed of sheet 50 metal, and having backwardly folded flanges 11 is slidably mounted upon the off-set ends 9 of the brackets 8 thereby permitting the track plate 10 to be conveniently and easily attached to the bracket 8. By means of the 55 connection of the track plate 10 to the frame or top 1, it will be seen, that the track plate

10 may be adjusted to suit the different sizes of the case or cabinet upon which the track is mounted.

A reel carrying clip or shoe is slidably 60 mounted upon this track plate 10 and is formed from a blank sheet of material and comprises a body 12 having backwardly folded and inwardly extending flanges 13 for fitting snugly over the track plate 10. 65 A pair of tongues 14 are struck from the body 12 and are bent at right angles to the body 12 and the reel casing 15 is mounted between these tongues 14 and soldered thereon for the purpose of efficiently supporting 70 the reel. From the foregoing description it will be seen that the track plate 10 may be adjusted upon the ends 9 to permit the same to accommodate itself to different size cabinets and it will be seen that the shoe may 75 be adjusted longitudinally upon the track plate 10 so as to have the tape reel 15 extend over any one of the tapes 7. A tape measure 16 is wound within the reel casing 15 and is provided with a suitable eye 17 80 upon its outer end. It of course should be understood that ribbon, tape, or elastic or in fact any material may be placed upon the reels 2 and when it is desired to measure the material, the material or tape 7 and the 85 end of the tape 16 are pulled together until the desired amount of material has been measured. The tape 7 may then be easily cut by releasing the tape measure 16, and the tape measure 16 will immediately recoil 90 95 itself within the casing 15. It of course should be understood that suitable means is employed within the casing 15 for the purpose of winding the tape measure 16 therein.

What is claimed is:—

1. In a device of the class described, the combination with a cabinet, of a track plate, end brackets adapted to support said track plate upon said cabinet, said end brackets 100 provided with off-set inwardly extending ends, said track plate provided with backwardly folded edges fitting over said inwardly extending ends of said brackets for permitting said brackets to be adjusted in 105 said track plate, and a reel carrying shoe slidably mounted upon said track plate.

2. In a device of the class described, the combination with a cabinet, of a track plate, end brackets adapted to support said track 110 plate upon said cabinet, said end brackets provided with off-set inwardly extending

ends, said track plate provided with backwardly folded edges fitting over said inwardly extending ends of said brackets for permitting said brackets to be adjusted in said track plate, a measuring reel, a reel carrying shoe slidably mounted upon said track plate and provided with backwardly folded flanges fitting around said track plate and permitting said reel carrying shoe to be

adjusted longitudinally upon said track 10 plate, and said reel carrying shoe provided with outwardly struck tongues fitting upon opposite sides of said measuring reel and constituting an efficient support for said measuring reel.

15

In testimony whereof I hereunto affix my signature.

SIEBOLD R. MENSSEN.

Copies of this patent may be obtained for five cents each, by addressing the "Commissioner of Patents, Washington, D. C."
